Assignor to

The Lowell Manufacturing Company of the same place.

Letters Patent No. 7775 Dated July 19th 1864.

Design for a Carpet Pattern.

The schedule referred to in these Letters Patent and making part of the same.

To all whom it may concern:

Be it known that G. E. Lewis J. Mey. of Lowell, in the County of Middlesex and State of Massachusetts, have originated and designed a new Pattern for carpets or other fabrics, of which the following is a full, clear and exact description, reference being had to the accompanying drawings, making part of this specification.

It is of one fourth a large set figure, the composition of which is shown in the drawing.

Is one fourth of a plain frame to the inner edge of which lace work is attached.

Frame D is similar to frame A.

In corners C and D are fourths of large set figures each composed of a square block, four rosettes surrounded by spires and a frame composed of a band of parallel lines, a solid band and lace-work.

In the centre of the drawing is a plain leaf.

The remaining figures are the vines.

The colors employed for the different portions of the design may be varied to suit the taste and wish of the manufacturer.

Claim.

What I claim as my invention, and desire to secure by Letters Patent is The Design or Pattern for carpets or other fabrics herein set forth.
